UNITED STATES PATENT OFFICE

JOHN C. CURTIS, OF EASTON, PENNSYLVANIA, ASSIGNOR TO INGERSOLL-RAND COMPANY, OF JERSEY CITY, NEW JERSEY, A CORPORATION OF NEW JERSEY

VALVE FOR ROCK DRILLS

Application filed February 19, 1930. Serial No. 429,554.

This invention relates to rock drills, but more particularly to a distributing valve for rock drills of the fluid actuated type.

The objects of the invention are to obtain a rapid and positive action of the valve, to assure a heavy blow against the working implement, and to minimize the volume of pressure fluid consumption for actuating the tool.

Other objects will be in part obvious and in part pointed out hereinafter.

In the accompanying drawings forming part of this specification and in which similar reference characters refer to similar parts,

Figure 1 is a sectional elevation of a rock drill equipped with a valve constructed in accordance with the practice of the invention, the valve being shown in position to supply pressure fluid to the rear end of the piston chamber, and

Figure 2 is a similar view showing the valve in a position for supplying pressure fluid to the front end of the piston chamber.

Referring to the drawings, the invention is shown embodied in a rock drill A comprising a cylinder B having a piston chamber C to receive a reciprocating hammer piston D. The cylinder B is provided with an exhaust port E intermediate its ends and the exhaust port E is in this instance controlled by the piston D.

Disposed at the front end of the cylinder B is a front cylinder washer F to form a closure for that end of the piston chamber C and to centralize a front head G with respect to the cylinder B.

An additional function of the front cylinder washer F is to act as a guide for an anvil block H which is disposed slidably in the front cylinder washer F. The anvil block extends into the front end of the piston chamber C to transmit the blows of the hammer piston D to a working implement J which may be suitably guided by the front head G.

In the rear end of the cylinder B is a bore K to receive a valve chest L which in this instance comprises outer and inner members O and P. The outer member O is in the form of a ring and is provided with a suitable bore Q for the accommodation of the inner member P. The members O and P may be seated upon

a plate R which is disposed adjacent the rear end of the piston chamber C to form a closure therefor.

Seated upon the members O and P is a back head S which may form the rearmost part of the casing A and like the front head G may be secured to the cylinder B by means of side bolts (not shown).

The back head S serves as a housing for a throttle valve T which may be of the rotary type and has a central chamber U into which pressure fluid may be constantly introduced from a source of supply.

In the wall of the throttle valve T is a port V to register with a supply passage W in the back head S in the members O and P and opening with its outlet end into a valve chamber X formed in this instance in the member P to accommodate a distributing valve Y. The valve chamber X comprises an enlarged portion Z which constitutes the front end of the valve chamber and a reduced rearward portion b into which extends a stem c of the valve Y.

The outlet opening of the supply passage W preferably opens into the enlarged portion Z of the valve chamber X at a point approximately midway between the ends of the enlarged portion Z. In the plate R and preferably arranged coaxially with the valve chamber X is a rear inlet passage d through which pressure fluid may flow into the rear end of the piston chamber C to actuate the piston D forwardly.

The pressure fluid supplied to the front end of the piston chamber C for actuating the piston D rearwardly is conveyed thereto by a front inlet passage e in the wall of the cylinder B, the plate R, the members O and P and opens into the valve chamber at the junction of the enlarged portion Z and the reduced portion b.

In order to lighten the valve Y, said valve may be provided with a recess f which in this instance opens from the front end of the valve Y, thus leaving a wall g at the rear end of the stem c. Near the front end of the valve Y are a pair of flanges h and j forming a space k therebetween which is in constant communication with the supply passage W.

The flange h may be termed the front flange and is provided with a plurality of ports o through which pressure fluid flows from the space h into the front end of the enlarged portion Z of the valve chamber for supplying the rear end of the piston chamber C . Similarly, the flange j is provided with a series of ports p through which pressure fluid flows from the space k to the inlet passage e for supplying the front end of the piston chamber C .

The ports p may, as illustrated, be of smaller area than the ports o so that a lesser amount of pressure fluid will be supplied within a given time to the front end of the piston chamber for actuating the piston D rearwardly than is supplied to the rear end of the piston chamber for actuating the piston D on its working stroke. This is desirable inasmuch that it enables the piston D to be moved rearwardly at a speed commensurate with the best efficiency of the drill, and at the same time it permits reversal of the piston at the end of its return stroke without causing excessive jars or shocks to the drilling mechanism.

The front end of the flange h constitutes a pressure area q against which pressure fluid may act tending to throw the valve Y rearwardly, and on the rear end of the flange j is a pressure area r against which the pressure fluid flowing through the ports p may act for throwing the valve Y forwardly. The pressure area r is of smaller area than the pressure area q .

Adjacent the pressure area r is a stepped portion s , the rear surface of which constitutes an actuating surface t which is intermittently exposed to compression flowing from the front end of the piston chamber C to assist the pressure fluid acting against the pressure area r for actuating the valve Y .

Additional means are provided for actuating the valve Y from one end of the valve chamber to the other. To this end the front end of the wall g serves as an actuating surface u against which compression from the rear end of the piston chamber may act to assist in throwing the valve Y rearwardly. The opposite side or rear end of the wall g likewise constitutes an actuating surface v which is intermittently exposed to pressure fluid to assist the pressure fluid acting against the surfaces r and t for throwing the valve Y forwardly. The pressure fluid thus acting against the actuating surface v is conveyed to the rear end of the reduced portion b of the valve chamber by a kicker passage w which communicates with its inlet opening or port x with the rear portion of the piston chamber C and preferably at a point closely adjacent the exhaust port E .

The reduced portion b of the valve chamber X is provided with an exhaust passage y which opens to the atmosphere and is so

located that it will be uncovered by the rear end of the valve when the valve approaches the front end of the valve chamber.

The operation of the device is as follows: With the valve in the rearmost position illustrated in Figure 1, pressure fluid will flow through the ports o into and through the front end of the valve chamber X , thence through the rear inlet passage d into the back end of the piston chamber to drive the piston D forwardly.

During the admission of pressure fluid into the rear end of the piston chamber pressure fluid will also pass through the ports p to act against the actuating surface r . Such pressure fluid acting against the actuating surface r however, will be ineffective to change the position of the valve Y as the valve is exposed to pressure fluid over its forwardly facing surfaces, such as the pressure area q and the actuating surface u . The valve will therefore remain firmly seated in the rear end of the valve chamber until the piston D uncovers the port x of the kicker passage w . This will take place immediately before the piston D uncovers the exhaust port E and pressure fluid will then flow through the kicker passage w into the rear end of the valve chamber to act against the actuating surface v .

Immediately upon the uncovering of the exhaust port E by the piston the pressure acting against the forward surfaces of the valve Y will drop considerably below line pressure. When this drop in pressure occurs the pressure or pressures acting against the surfaces v and r , together with the compression which flows from the front end of the piston chamber C to act against the actuating surface t , will move the valve Y forwardly to close the inlet passage d .

This movement of the valve Y may take place slightly prior to the instant of impact of the hammer piston D against the anvil block H so that an immediate supply of pressure fluid may be introduced into the front end of the piston chamber C to return the piston D . The pressure fluid serving to return the piston D flows from the space h between the flanges through the ports p and thence through the rear end of the enlarged portion of the valve chamber and the front inlet passage e to the front end of the piston chamber C .

During the admission of pressure fluid to the front end of the piston chamber the valve Y will be momentarily held stationary in the front end of the valve chamber by the pressure fluid acting against the surfaces r and t . The pressure fluid previously admitted into the rear end of the reduced portion of the valve chamber may be exhausted therefrom through both the kicker passage w and through the exhaust port E , and also through the exhaust passage y .

As the piston D moves rearwardly and after it covers the exhaust port E the air in the rear end of the piston chamber C will be compressed. This compression will act against the actuating surface u and, together with the pressure fluid acting against the actuating surface q , will move the valve to its initial position for admitting pressure fluid into the rear end of the piston chamber C.

10 I claim:

1. In a fluid actuated rock drill, the combination of a cylinder having a piston chamber and a hammer piston in the piston chamber, an exhaust port in the cylinder, a valve chest having a valve chamber, inlet passages leading from the valve chamber to the piston chamber, a valve in the valve chamber controlling the inlet passages, a pair of flanges on the valve having apertures therein through which pressure fluid flows to the inlet passages, a supply passage in the valve chest for introducing pressure into the valve chamber between the flanges, pressure areas on the flanges against which the pressure fluid flowing through the apertures acts for throwing the valve, opposed actuating surfaces on the valve, one of said actuating surfaces being intermittently exposed to compression to assist in throwing the valve in one direction, and a kicker passage leading from the cylinder to the valve chamber and controlled by the piston to expose the other actuating surface to pressure fluid for assisting in throwing the valve in the opposite direction.

35 2. In a fluid actuated rock drill, the combination of a cylinder having a piston chamber and a hammer piston in the piston chamber, an exhaust port in the cylinder, a valve chest having a valve chamber, inlet passages leading from the valve chamber to the piston chamber, a valve in the valve chamber to control the inlet passages, a pair of flanges on the valve having pressure areas on their outer ends, said flanges having ports for supplying pressure fluid to the pressure areas for throwing the valve and for supplying pressure fluid to the inlet passages, a supply passage in the valve chest for supplying pressure fluid to the valve chamber between the flanges, opposed actuating surfaces on the valve, one of said actuating surfaces being intermittently exposed to compression to assist in throwing the valve for admitting pressure fluid to the rear end of the piston chamber, and a kicker passage leading from the rear end of the piston chamber to the valve chamber and controlled by the piston to expose the other actuating surface to pressure fluid to assist in throwing the valve for admitting pressure fluid to the front end of the piston chamber.

In testimony whereof I have signed this specification.

JOHN C. CURTIS.
